UNITED STATES PATENT OFFICE

PETER AURICH, OF BOCHUM, GERMANY, ASSIGNOR TO GEBR. EICKHOFF, MASCHINEN-FABRIK U. EISENGIESSEREI, OF BOCHUM, GERMANY

SHAKING CONVEYING DEVICE

Application filed July 20, 1928, Serial No. 294,219, and in Germany July 20, 1927.

My invention relates to shaking conveyers and has for its object to improve them as to their connection to the driving motor. To connect shaking conveyers to their driving motors, a conveyer element of special construction is hitherto employed in most of the cases, which element is equipped with special means for connecting it and therewith the entire shaking conveyer to the driving motor.

- 10 My invention has for its object to allow of such a special connecting conveyer element to be dispensed with and of the driving motor to be attached to any normal element of the conveyer. To this end I provide as connection between the motor and the conveyer a body that reciprocates in suitable guides and is fitted with means for connecting it to the motor, while it is further so constructed that it may be united to the normal means 20 that interconnect the individual elements of the shaking conveyer.

In order to allow of my invention to be more easily understood, some preferred embodiments of same are illustrated by way of 25 example in the drawings which accompany and form part of this specification.

In these drawings:

Figure 1 is the top view of the first embodiment of the body serving to connect the 30 motor with the conveyer,

Figure 2 is a similar view of another embodiment,

Figure 3 shows a third embodiment in the top view,

35 Figure 4 is an elevation thereof, partly in section, in conjunction with the shaking conveyer, while

Figure 5 is a corresponding front view.

Referring to these figures, *r* denotes the 40 shaking conveyer, while *a* is the body that serves to connect the conveyer *r* to the motor. This body *a* is guided on a bed frame *k* by means of antifriction rollers *f* in vertical direction and by a similar roller *f'* in lateral 45 direction. By means of lugs *b* the body *a* may be connected to the means that normally unite the individual elements of the shaking conveyer *r*, e. g. to the normal connecting bolts *c*, see particularly Figures 4 and 5.

50 In order to enable the described body to be

used with conveyers of different dimensions or construction, it will be of advantage to provide in the lugs *b* a plurality of holes *b'*, *b''*, Figure 5, that may be used selectively in engaging the connecting bolts *c*. Furthermore, these holes may be open, as illustrated in the left-hand portion of Figure 5, this affording the advantage that the body *a* and conveyer *r* may be connected with or separated from, one another and the body *a* attached at any desired place of the conveyer *r* without removing to this end the bolts *c* that connect the individual conveyer elements.

The body *a* is further fitted with means for connecting it to the driving motor (not shown), viz. e. g. a central thrust rod *d*, Figure 1, or a rope or chain, to connect it to a motor located below the conveyer, or a straight or double lever *h*, Figure 2, when the driving motor is arranged laterally of the 70 conveyer. As further illustrated in Figures 3 and 4, these two connecting members *d* and *h* may be provided on the body *a* in unison, to be used selectively, as the case may be. To eliminate tipping or canting, the body *a* may 75 carry a set screw *i* or a suitable equivalent means, that abuts on the conveyer *r*. The provision of two connecting means, as *d* and *h*, Figures 3 and 4, further enables two or more bodies *a* to be interconnected by a suitable system of rods, in order to distribute the power delivered from the motor on a plurality of conveyer elements.

What I claim and desire to secure by Letters Patent is:

1. In a shaking conveyer of the character described the combination of a pair of coupled conveyer sections and the motive means for shaking the sections, of a reciprocable body member positioned underneath the sections and connected to the coupling means, and means for retaining the reciprocable body member against extended movement in either a vertical or transverse horizontal direction.

2. In a shaking conveyer of the character described the combination of the conveyer member and the motive means for shaking the member, of a reciprocable body member positioned underneath the conveyer member

and upon which the conveyer member is supported and attached, and means for retaining the reciprocable body member against extended movement in either a vertical or transverse horizontal direction.

3. A conveyer section supporting body member for a shaking conveyer of the character described comprising a portion upon which the conveyer is supported and to which it is attached, a plurality of rollers mounted upon said portion, a plurality of tracks of channel-shaped cross section in which the rollers are contained, said rollers and tracks providing means whereby the

15 body member is free to roll in a longitudinal horizontal direction but retained against movement in a vertical or horizontal transverse direction.

4. A conveyer section supporting body member for a shaking conveyer of the character described comprising a portion upon which the conveyer is supported and to which it is attached, a plurality of rollers, a pair of vertical rollers mounted upon the 20 sides of the portion, a pair of parallel tracks of U-shape cross section into which the rollers extend and by means of which the body member is retained against vertical movement, a horizontal roller mounted upon the bottom 25 of the body member, a central track of U-shape cross section into which the roller extends and by means of which the body member is retained against transverse horizontal movement, and means upon the upper portion 30 of the body member constituting a connection between such body member and the conveyer sections.

In testimony whereof I affix my signature.
PETER AURICH.
